UNITED STATES PATENT OFFICE

VICTOR KALFUS, OF NEW YORK, N. Y.

FLUID HEATING DEVICE

Application filed October 28, 1929. Serial No. 402,927.

The present invention relates to heating devices for air or water, which are adapted to be attached to the flue pipe of a furnace or the like.

One object of the present device is to provide means for utilizing the waste heat which usually escapes with the flue gases of a furnace.

Still another object is to provide a device with regulating means therein whereby it will be possible to vary the temperature of the fluid heated.

Still another object is to provide means which may readily be attached in common heating systems with little cost.

A further object is to provide a device which may be manufactured at low cost.

With the above and other objects in view my invention consists in the novel construction, combination and arrangement of elements which will hereinafter be more fully described, shown in the accompanying drawing and claimed in the appended claims.

In the drawing which forms part of this specification and in which similar reference characters denote corresponding parts,

Fig. 1 is a sectional elevation of my device in position of use; Fig. 2 is a section along line 2—2 of Fig. 1 seen in the direction of the arrows; Fig. 3 is a section along lines 3—3 of Fig. 1 also seen in the direction of the arrows; Fig. 4 is a partial sectional elevation of a modified form of my device; and Fig. 5 is a partial top plan view of said modified form with the cover removed.

In the drawing, 10 denotes a flue pipe from a furnace F. Adapted to be mounted on said pipe 10 is my heating device which may comprise a main casting 11 of brass or any other suitable metal. The said casting is provided with a central opening 12 the diameter of which is approximately equal to that of the flue pipe. Formed around said central opening is a concentric fluid compartment 13 which has a horizontal annular partition 13' arranged therein which divides the said compartment into two separate chambers A and B. Also formed in said compartment is a vertical partition 13". A suitable opening 13' is provided in partition 13' on one side of

the partition 13". An inlet 13* is provided in the lower chamber A on the opposite side of said partition 13" as said opening 13'. Similarly an outlet 13* is provided for the upper chamber B on the opposite side of said partition 13" of said opening 13". Thus fluid entering inlet 13* flows around chamber A until it reaches partition 13" whereupon it passes up through opening 13", into chamber B and around through chamber B in the opposite direction to the direction of flow in chamber A until it reaches the partition 13" whereupon it passes on through outlet 13*.

Suitably spaced from the outer wall of said compartment 13 as by means of spacers 14 is a jacket 15 which may be integrally formed with the previous elements if desired.

Suitably attached at the ends of said casting or integrally formed therewith are covers 16 and 17 respectively provided with central openings of approximately the same dimensions as said flue pipe and having collars 16' and 17' respectively formed at said openings, said collars being adapted to engage the flue pipe 10 whereby my device may be mounted between sections of said pipe.

The gases passing through the flue pipe normally would flow through the central opening 12 of the casting. In order to direct part of said gases through the channel E between jacket 15 and the compartment 13, I provide a deflecting arrangement at the lower end of opening 12. In the present embodiment this is shown as comprising a plurality of shutter blades 18 each pivotally mounted in an annular projection 12' formed at the lower end of said opening 12 by means of pivoting rods 19, and fixedly mounted to said rods. Fixedly mounted to said rods at the free end thereof which project through said collar 12' are levers 20. Each of said levers 20 pivotally engages an operating rod 21 in such manner that all the blades 18 may be simultaneously adjusted in shutter-like fashion to various angles by lateral motion of said rod, thereby correspondingly increasing or decreasing the amount of gas which may freely pass through opening 12. With a constant draft a decrease in the quantity of flue gas which may pass

through opening 12 causes the balance of said flue gas to pass through the channel E.

Suitably arranged in the collar 17' are pivoted dampers 21 operable from the outside by means of handles 21'. When the said dampers are on the horizontal position shown they tend to slow up the passage of the flue gas through the heater and thereby cause the gases to give off more of their heat and consequently raise the temperature of the heated fluid in chambers A and B.

The temperature may further be regulated by the shutter-like members 18, for by increasing or decreasing the passage of the flue gas between jacket 15 and compartment 13, correspondingly more or less heating of the fluid in chambers A and B will result.

In order to increase the capacity of my heater I may employ the modification of Figs. 4 and 5. In this modification in addition to the structure provided in the first modification, I provide an additional concentric compartment 22 spaced from compartment 13 and which is divided into two chambers C and D by a horizontal partition 22'. A vertical partition 22² similar to partition 13² and for the same purpose is provided for this compartment. An opening 22³ is provided in partition 22' on one side of partition 22³. An inlet 22⁴ to chamber D is provided on the opposite side of partition 22² as said opening 22³. An outlet 22⁵ is provided for chamber C which is also on the opposite side of partition 22² from said opening 22³ and said outlet 22⁵ is joined to outlet 13⁵ of chamber B, by pipe 23. Inlet 22⁴ is joined to the inlet 13⁴ of chamber A by a pipe 23'.

The fluid enters through pipe 23' part thereof flowing into chamber D and the balance into chamber A. The fluid in each of said chambers flows around the said chambers, up through the respective openings 13³ and 22³ around the said chambers B and C in direction opposite to the flow in chambers A and D and out through the respective outlets 13⁵ and 22⁵ and thence through the common pipe 23. It will be seen that in effect the two compartments are in parallel arrangement relative to the fluid flow. Part of the fluid passing through one compartment and the balance through the other.

In this modification a floor 24 is provided for the space E' between the compartments 22 and 13, and a plurality of holes 24' are provided in said floor. Mounted below said floor is a slidable annular ring 25 also provided with a plurality of holes 25' which may be caused to register with holes 24' by rotation of said ring 25. To so rotate said ring a handle 26 fastened thereto and projecting outwardly through slot 26' in my device is provided. This means is provided for limiting the flow of flue gases through the space between two compartments 13 and 22 and there-

by affording means for regulating the temperature of the fluid heated.

In both devices if air instead of water is to be heated, the size of the fluid compartments may be increased.

In all of my modifications if desired the outer surfaces may be covered with heat insulating material in well known manner.

My invention may be modified in various other ways without departing from the spirit thereof and I do not wish to be limited to the details shown and described.

What I claim is:—

1. A fluid heater adapted to utilize waste gases of a furnace or the like comprising a 80 casing having a hollow center portion, a partitioned compartment about said hollow center portion, a second concentric partitioned compartment about said first named compartment and spaced therefrom, fluid being adapted to flow through said two compartments, a damper located at the bottom of said hollow center portion for controlling the flow of gas therethrough and a second damper in the space between said two compartments 90 whereby the temperature of the fluid flowing in said compartments may be controlled.

2. A fluid heater adapted to utilize waste gases from a furnace or the like, comprising a casting having a hollow center portion, a compartment about said center portion, a second compartment spaced from said first named compartment, inlet and outlet means for each of said compartments, a horizontal and vertical partition in each of said compartments dividing each of the latter into two chambers, said partitions having openings whereby fluid may flow through from one to the other of the respective chambers, a damper in said central portion for controlling the flow of gas therethrough, a damper in said space between said two compartments for controlling the flow of gas therethrough whereby the temperature of the fluid flowing in said compartments may be regulated, and means for mounting the said heater in a waste gas pipe.

In testimony whereof I affix my signature.

VICTOR KALFUS.
